UNITED STATES PATENT OFFICE.

JOHN A. ADLER, OF NORTH MILWAUKEE, WISCONSIN.

TAIL OR SIGNAL LIGHT CONSTRUCTION.

Application filed June 5, 1924. Serial No. 718,110.

To all whom it may concern:

Be it known that I, JOHN A. ADLER, a citizen of the United States, residing at North Milwaukee, in the county of Milwaukee and State of Wisconsin, have invented 5 certain new and useful Improvements in Tail or Signal Light Constructions, of which the following is a specification, reference being had to the accompanying drawings.

This invention relates to tail or signal light constructions and has for a particular object thereof the construction of such devices so that aberration of rays is eliminated. 15 This aberration of rays as directed from signal lights, and particularly those signal lights employing a stencil against a transparent sheet through which the light rays are directed, causes merging and blurring of the characters of the signal so as to render them undecipherable and is accordingly the chief argument against construction of this type of signal. Hitherto the construction of reflectors employed in 20 these signals has been such that this aberration is in no way corrected.

An important object of this invention is the provision of a reflector in combination with a casing, the combination being such 30 that all of the light rays from an illuminating element disposed between the reflector and the opposite wall of the casing are directed toward such wall of the casing at right angles to the wall and accordingly 35 have no tendency to merge and blur.

A still further object of the invention is to provide a device of this character which may be as simply and readily produced as other reflectors employed in headlights at 40 present.

A still further object of the invention is the provision of a reflector for use in elongated narrow signal boxes which is in the form of a section of a circular parabolically 45 curved reflector which includes the principal vertex of parabolic curvature.

These and other objects I attain by the construction shown in the accompanying drawings, wherein for the purpose of illustration is shown a preferred embodiment of 50 my invention and wherein:—

Figure 1 is a perspective view of a signal constructed in accordance with my invention;

Figure 2 is a longitudinal sectional view 55 therethrough;

Figure 3 is a transverse sectional view taken approximately centrally thereof:

Figure 4 is an enlarged detail sectional view showing the manner of securing the 60 various parts of the signal in position.

Referring now more particularly to the drawings, the numeral 10 indicates a rectangular casing having one open side which is closed by a removable cover plate 11. 65 Within the casing is arranged a reflector 12 facing this removable wall or cover and this reflector is in the form of a section of a circular parabolically curved reflector including the principal vertex of parabolic curvature. At this vertex the rear wall 13 of the casing is tangential to the rear face of the reflector and is secured to the reflector by means of lock nuts 14 mounted upon a socket 15 which is coaxial with the reflector 70 and which is adapted for the reception of a lighting globe 16. The width of the section of the reflector employed is slightly less than the depth of the casing and the edges of this reflector are provided with outstanding stiffening flanges 17 perpendicular to the walls of the casing and directed toward these walls. Those portions of the casing lying within the limit defined by the open side of the casing and the flange 17 are coated, as at 18, with a coating of light absorbing 85 material such as a dull black paint.

The casing has secured thereto at points spaced inwardly from the open side thereof and paralleling these open sides angle braces 90 or lugs 19 one angle of which is secured to the wall of the casing by rivets or the like, as at 20, and the other wall of which stands out from the casing to provide a ledge. One of these lugs is arranged upon each wall of 95 the casing, the two lugs at the end walls 21 of the casing being spaced inwardly from the edge of the open side of the casing a distance equal to the thickness of the material from which the reflector is formed. The 100 end edges of the reflector are provided with outstanding flanges 22 abutting the lugs of the end walls. Abutting the flanges 22 and the remaining lugs 19 is a rectangular framework 23 formed from stiff sheet metal 105 and which serves as a support for a similarly shaped gasket or padding member 23a. Against the outer surface of the padding member is arranged a lens plate 24 which may be in the form of a thin sheet of celluloid of the desired color or which may be of glass if desired. Against the outer sur- 110

face of the lens sheet is arranged an indicator or stencil plate 25 which is perforated to provide indicia 26 through which the lens plate 24 is exposed. The cover 11 is formed with openings 27 exposing the indicia of the indicator plate. This cover is secured in position by means of screws 28 directed through aligned openings formed in the cover, indicator plate, lens plate, gasket and frame and threaded into openings formed in the lugs 19. Any suitable means can be employed for securing the signal box in adjusted position. In the present instance I have shown brackets 29 attached to the signal box and having openings for the reception of securing elements whereby the brackets may be attached to a suitable support. This means, however, may be varied to suit the mounting requirements to be met.

20 It will be seen that by the construction set forth all light emanating from the illuminating element 16 will be directed either against the walls of the reflector, that portion of the casing lying between the reflector and the cover, or against the cover. Of course, those portions of the rays from the light proper which are not refracted will pass directly through the indicia openings 26 but these rays are not dazzling and will not cause sufficient aberration to render the signature illegible. Of the remaining rays those striking the reflector will, of course, be directed back against the cover at right angles to the cover and being parallel as they pass from the casing will not tend to merge at any point whatever. Those rays striking the walls of the casing lying between the reflector flange 17 and the cover plate will be absorbed or deadened by the coating 18 to such an extent as to render them innoxious. It will furthermore be noted that by the construction hereinbefore set forth a signal is provided which may be readily constructed from stamping and in which all parts are capable of construction by this method with the exception of the formation of the lugs 19 which may be any common stock angle iron or may be cast from aluminum as desired.

50 It will furthermore be obvious that this construction is capable of a certain range of change and modification without materially departing from the spirit of my invention and I accordingly do not limit myself to such specific structure as hereinbefore set forth except as hereinatfer claimed.

I claim:

1. In a signal construction of the type described and in combination, a rectangular casing having one wall provided with a lens, 60 a reflector within the casing comprising a section of a circular parabolically curved reflector including the principal vertex of parabolic curvature, said reflector opposing the lens bearing wall, the walls of the casing 65 at the sides of the reflector section being coated with a light absorbing material.

2. In combination with a rectangular casing having a lens bearing wall, a reflector within the casing having its ends terminating immediately adjacent the lens bearing wall and parabolically curved intermediate its ends whereby the lens bearing wall, the reflector and the walls of the casing between the reflector and the lens bearing wall form 75 a light compartment, those portions of the casing forming walls of the light compartment being interiorly coated with a light absorbing material.

3. In combination with a rectangular casing having a lens bearing wall, a reflector within the casing having its ends terminating immediately adjacent the lens bearing wall and parabolically curved intermediate its ends whereby the lens bearing wall, the 85 reflector and the walls of the casing between the reflector and the lens bearing wall form a light compartment, those portions of the casing forming walls of the light compartment being interiorly coated with a light 90 absorbing material, said reflector being parabolically curved at right angles to its end to end axis.

4. In combination with a rectangular casing having a lens bearing wall, a reflector within the casing having its ends terminating immediately adjacent the lens bearing wall and parabolically curved intermediate its ends whereby the lens bearing wall, the reflector and the walls of the casing between 100 the reflector and the lens bearing wall form a light compartment, those portions of the casing forming walls of the light compartment being interiorly coated with a light absorbing material, the longitudinal edges of 105 the reflector being provided with stiffening flanges directed toward the last named portions of the casing.

In testimony whereof I hereunto affix my signature.

JOHN A. ADLER.
